(57) **CLAIM**

The ornamental design for a spinal distraction structure, as shown and described.

DESCRIPTION

FIG. 1 is an overhead isometric view of the front, top, and side of a spinal distraction structure showing our new design;

FIG. 2 is a top view thereof;

FIG. 3 is a side view, with the opposite side being a mirror image thereof;

FIG. 4 is a front view thereof;

FIG. 5 is a rear thereof;

FIG. 6 is an overhead isometric view of the front, top, and side of a second embodiment of a spinal distraction structure, in which the height and length are of indeterminate dimensions;

FIG. 7 is a top view thereof;

FIG. 8 is a side view, with the opposite side being a mirror image thereof;

FIG. 9 is a front view thereof; and,

FIG. 10 is a rear view thereof.

The broken lines shown are for illustrative purposes only and form no part of the claimed design.
